US0D1080619S

(12) United States Design Patent (10) Patent No.: US D1,080,619 S
(45) Date of Patent: * Jun. 24, 2025

(54) SMARTWATCH

(71) Applicant: Shenzhen Kule Times Technology Co., Ltd., Guangdong (CN)

(72) Inventor: Zhenyong Deng, Guangdong (CN)

() Term: 15 Years

(21) Appl. No.: 29/979,920

(22) Filed: Dec. 20, 2024

(30) Foreign Application Priority Data

Jun. 22, 2024 (EM) 015064380-0001

(51) LOC (15) Cl. 14-02

(57) CLAIM

The ornamental design for a smartwatch as shown and described.

DESCRIPTION

FIG. 1 is a front perspective view of a smartwatch showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is a rear perspective view thereof;

FIG. 9 is an enlarged detail view taken from portion 9 of FIG. 1;

FIG. 10 is an enlarged detail view taken from portion 10 of FIG. 1;

FIG. 11 is an enlarged detail view taken from portion 11 of FIG. 2;

FIG. 12 is an enlarged detail view taken from portion 12 of FIG. 6; and,

FIG. 13 is an enlarged detail view taken from portion 13 of FIG. 8.

The broken lines encircling portions of the smartwatch in FIGS. 1, 2, 6, 8 and illustrated in enlarged views in FIGS. 9-13 form no part of the claimed design.

1 Claim, 13 Drawing Sheets
